TOILET CASE

George Miller, Wellesley, and Emil K. Renz, Dedham, Mass., assignors to Knight Leather Products, Inc., Boston, Mass., a corporation of Massachusetts

Application January 24, 1952, Serial No. 267,966

6 Claims. (Cl. 150—34)

1

The present invention relates to toilet cases made of flexible, yielding material as contrasted with stiff boxes and cases made of metal, wood, stiff plastic material and other composition material, but actually the invention may be used in small types of cases for toilet or for other purposes.

The object of the present invention is to provide a case in which the cover, when unlatched, will automatically open and hold its open position. The object of the present invention is to construct a case of flexible, yielding material without any rigid frame which will maintain sufficient rigidity so that it is not readily deformed and will thereby serve fully its purposes. A further object of the present invention is to provide a toilet case in which the cover will automatically open when unlatched and in which the body of the case will retain its form in which the side walls are substantially upright when the case is resting on its base in an open position.

The tendency of most leather or leather-like toilet cases, unless reinforced by steel angle elements, is for the back wall to which the top of the case is hinged, to tilt or bend, either forwards or backwards, thus spoiling the appearance of the case when it is opened. In the present application this is overcome without the use of reinforcing angle elements between the upright side wall and the bottom of the case so that the true flexibility and softness of the case is fully preserved.

A further object of the present invention is the arrangement of a torsion spring between the top cover of the case and the short upright wall to which the cover is hinged, the action of the torsion spring being such that the torsional element runs lengthwise of the flexible hinge and has its ends attached respectively to the cover and to the back. The present invention employs a pair of torsional springs which may be arranged either in alignment with the other or in parallel relation one with the other, the portion in alignment or in parallel relation being in a position of the hinging pivot.

The present invention will be more fully described in the specification set forth below when taken in connection with the drawings showing an embodiment of the invention, in which:

Figure 1 shows a perspective view of a toilet case of the present invention in an open position viewed from the rear and looking downward slightly with portions broken away to show the internal construction.

Figure 2 shows a section taken in a central region of the case, and,

2

Figure 3 shows a modification of the spring structure illustrated in Figure 1.

In the arrangement indicated in the drawings, the toilet case 1 may be covered on the outer surface with leather, pliable plastic, textile or composition material. On the inside, toilet cases of the present type are usually lined with a soft suede leather, cloth, plastic or other similar materials. These elements form the outer and inner wall of the case which may be of a size to contain comb, brush, shaving equipment and other useful accessories as toilet articles. For this purpose the long dimension of the case may be about 10" x 6" and the height approximately 2". These dimensions however may vary considerably, but the invention is intended to be used more particularly where the upright walls 2, 3, 4 and 5 are small in comparison to the other dimensions, as for instance, the bottom 6 and the cover 7. The case therefore may be described as a comparatively flat case with a large cover and low side walls. It will be seen from this arrangement that the cover 7 which is hinged to the back wall 4 as will be described later, is of a considerable size and weight, particularly if it is in any way fitted with mirrors, combs, etc. The problem therefore is to make the cover snap up and stay up while the case is in use and this must be done without making the case clumsy or having spring or any other elements bulge outward or inward from the flexible walls. As shown in Figures 1 and 2, the case is lined on the inner side with a thin, soft covering element 8, which as stated, may be of soft leather or fabric and on the outer side with a cover element 9 which may be of any desired kind of leather, imitation leather, plastic composition or textile material.

Referring more particularly to the composition of the cover 7, it will be noted that this comprises two stiff board members 10 and 11, which may be cardboard, stiff leather composition or some other somewhat yielding and somewhat flexible material. The boards 10 and 11 are cut out along a section 12 at their hinging ends opposite the edges of the lower back wall 4 as indicated in the copending application Serial No. 188,965, filed October 7, 1950, providing projecting end parts 13 which abut the top edges of similar stiff wall boards 14 and 15 forming portions of the back wall 4. The stiff boards 14 and 15 of the short upright back wall have between them a strong fabric sheet 16, to which each of the boards 14 and 15 is cemented. The sheet 16 extends downward from between the walls 14 and 15 and extends beneath the stiff sheet 17.

which is in the base wall 6 of the case. As will be seen from Figure 2, this sheet 16 extends quite far into the base beneath the stiff cardboard 17 and is cemented to it on its outer side. The stiff board 14 in the back of the case may be slightly skived at its lower edge to make a slight allowance for the bend in the bottom of the case so that this may be uniformly rounded.

However in the construction of the case, the boards 15 and 17 are positioned in flat abutting relation side by side and the sheet 16 is cemented over the two boards 15 and 17 in this abutting relationship. Thereafter the two boards 15 and 17 are bent upwards at right angles as indicated in Figure 2 so that the section of the material in the corner 18 is compressed and under some stress. On the back of the boards 14 and 17 a layer of soft filling material 19 is used, and on this is placed an outside covering 9 while on the inside is cemented the inner covering 8. This particular construction of the lower portion of the back gives the back wall 4 of the case a slight compressional stress which reacts to prevent a forward bending of the wall 4 near the hinging joint. This is essential to provide the proper strength and a square corner between the back and the bottom when no reinforcing angle brackets are to be used between the back and the base. This is particularly true in the type of case of the present invention where the side walls 3 and 5 at the ends of the case are soft and flexible and lack the stiff reinforcement that is used in the back wall 4. The walls 3 and 5 are lined on the inside and the outside with covering material, but very little, if any reinforcement is used in the wall itself as it is highly desirable to permit these walls to be flexible.

Referring again to the cover and the back walls of the case, it will be seen from Figure 1 and Figure 2, that the flexible hinge is provided by the fact that the stiff cardboard pieces 10 and 11 in the cover, and 14 and 15 in the back wall are independent and that the attachment of the cover and the back wall is obtained through the outer and inner cover element 9 and 8 respectively, and by the cut away section 12 as mentioned above.

A spring hinge element is provided between the cover and the back wall. As indicated in Figures 1 and 2 this is provided by two spring elements 20 and 21, each of which is composed of a long stem section running a considerable part of the length of the case along its hinge with the arms 22 and 23 at right angles but in the same plane with the stem 20 and the arms 24 and 25 similarly bent at right angles to the stem 21 but in the same plane as the stem. Each spring element therefore has the appearance of an elongated T with the angle bent at right angles to the stem. The stems of both springs 20 and 21 are encased in a sleeve 26 which has a flange 27 extending from the outer surface of the sleeve by means of which the sleeve is stapled, with staples 28 to the board 10. The springs themselves are held in place by stapling the arms 22 and 25 to the cover boards 10 and the arms 23 and 24 to the cover board 14 with the stems lying on the inside of these cover boards so that the stems themselves actually come between the cover boards 10, 11 and 14, 15 respectively. The ends of the staples as shown in Figure 1 are covered over by the filling material 19 so that the hardness of the turned over ends of the staples are well protected against marking the cover. The cover material 9 is drawn over the edges of the cover, the

back wall and the base, and a continuous line of stitching 29 stitches the cover material securely to the walls. The closure element is preferably provided by a "zipper" or any interlocking fasteners 30 mounted on a tape 31 in the usual fashion, one edge of which is stitched by the stitching 29 for the cover and by the stitching 32 to the three sides 2, 3 and 5. The springs 20 and 21 are in an untensioned position when the case is opened with the cover upright. As the cover is closed, the two arms 22 and 23 of the spring 20 rotating relatively about the axis through the stem of the spring, have an angle approximately 90° and similarly for the spring 21. In this position of the spring, the case is closed and when the interlocking fasteners are closed together, they will hold the cover tensioned in this position. When the fasteners are unlocked the case will again fly open to the position indicated in Figure 1.

A somewhat modified arrangement is shown in Figure 3. In this case each torsion spring 33 and 34 is approximately one-half as long as that shown in Figure 1. The stem sections 35 and 36 are positioned along the hinge section 37 in alignment one with the other. The spring 34 has arms 38 and 39 bent at right angles but in the same plane with the stem 36 and the spring 33 has arms 40 and 41 also bent at right angles with the stem 33 and in the same plane. The arms 38 and 40 are longer than the arms 39 and 41 respectively, being approximately twice their length and these arms 38 and 40 are securely held by staples 42 and 43 to the board 10 of the cover 7 so that the arms 38 and 40 do not move with respect to the cover board 10. However the arms 39 and 41 are held to the board 14 of the back wall by comparatively loose staples 44 and 45 so that the arms 39 and 41 are free to slide through the staples as the cover is opened and closed.

It has been found that a slight freedom of motion is desirable and that this freedom provided by tolerances given in setting the staples, permits the cover to be opened and closed without causing bulges at the hinge in the cover or in the back. In the arrangement indicated in Figure 3, it is not necessary to fix the stems of the spring in a cover and, further, the construction in Figure 3 does not make it necessary for one stem to cross over the other stem as is necessary in Figure 2, since in this construction the arms of each spring extend in opposite directions. An advantage however in the construction of Figure 1, is that a longer spring may be used and therefore the torsion in the stem is taken up in this longer length. Both constructions in Figures 1 and 2 have however been found to be very satisfactory. While it is desirable to use only a single spring, the use of a double spring has the advantage of providing better balance and is favored in the construction.

In the arrangement shown in Figure 3, the two arms 38 and 40 are side by side in the cover. This construction may be reversed and the arms 65 may be placed at the sides of the cover with the arms in the back adjacent one another. The arms in both cover and back may be separately stapled and the arms in the cover may be sufficiently loosely held so that they may slide.

Having now described our invention, we claim:

1. A toilet case having a bottom wall member, a back wall member, flexible side walls adjoining the back wall member and a front wall forming the walls surrounding the bottom wall member, and a cover member having a flexible fabric hing-

ing connection with the back wall member, said back wall member and said cover member having laminated flexible stiffening sheets, torsional spring means having a torsional stem positioned along the hinging connection with arms secured respectively to said cover member and said back wall member, said torsional spring means being untensioned when the cover is in an open position and tensioned when in a closed position, and means for holding said cover in a closed position.

2. A toilet case having a bottom wall member, a back wall member, flexible side walls adjoining the back wall member and a front wall forming the walls surrounding the bottom wall member, and a cover member having a flexible fabric hinging connection with the back wall member, said back wall member and said cover member having laminated flexible stiffening sheets, a pair of torsional springs having stem sections extending along the hinging connections, each with an arm secured to the cover member and one secured to the back wall member, together with the stem section forming a letter H when the cover is opened, said springs being untensioned in the open position of the case and closed in a tensioned position, and means for holding said cover in a closed position.

3. A toilet case having a bottom wall member, a back wall member, flexible side walls adjoining the back wall member and a front wall forming the walls surrounding the bottom wall member, and a cover member having a flexible fabric hinging connection with the back wall member, said back wall member and said cover member having laminated flexible stiffening sheets, a pair of torsional springs having stem sections extending along the hinging connections, each with an arm secured to the cover member and one secured to the back wall member, together with the stem section forming a letter H when the cover is opened, a flexible sleeve member encasing said stems together having a flange extending outward of the sleeve along its length secured to said cover, said spring being untensioned in the open position of the case and closed in a tensioned position, and means for holding said cover in a closed position.

4. A toilet case having a bottom wall member, a back wall member, flexible side walls adjoining the back wall member and a front wall forming the walls surrounding the bottom wall member, and a cover member having a flexible fabric hinging connection with the back wall member, said back wall member and said cover member having laminated flexible stiffening sheets, a pair of torsional springs each having a stem with arms extending from the ends of the stem in an angular position both in the same plane as the stem

when the spring is untensioned, the stems being positioned substantially in alignment along the hinging connection, said spring being untensioned in the open position of the case and closed in a tensioned position, and means for holding said cover in a closed position.

5. A toilet case having a bottom wall member, a back wall member, flexible side walls adjoining the back wall member and a front wall forming the walls surrounding the bottom wall member, and a cover member having a flexible fabric hinging connection with the back wall member, said back wall member and said cover member having laminated flexible stiffening sheets, a pair of torsional springs each having a stem with arms extending from the ends of the stem in an angular position both in the same plane as the stem when the spring is untensioned, the stem being positioned substantially in alignment along the hinging connection with two arms secured to the cover in its central region adjacent one another and two arms secured to the back at the opposite sides, said springs being untensioned in the open position of the case and closed in a tensioned position, and means for holding said cover in a closed position.

6. A toilet case having a bottom wall member, a back wall member, flexible side walls adjoining the back wall member and a front wall forming the walls surrounding the bottom wall member, and a cover member having a flexible fabric hinging connection with the back wall member, said back wall member and said cover member having laminated flexible stiffening sheets forming a central core of said cover member and said back wall member with continuous outer and inner covering sheets extending over the both faces respectively of the cover and the back wall forming said hinging connection, torsional spring means for said hinging connection having a portion secured between the laminated sheets of the cover and a portion between the laminated sheets of the back wall, said spring means being untensioned when the cover is in an open position and tensioned when in a closed position, and means for holding said cover in a closed position.
